(57) CLAIM

I claim the ornamental design for utility lighter portions, as shown and described.

DESCRIPTION

FIG. 1 is a front/right-side/top perspective view of utility lighter portions showing my new design in a standing position; and,

FIG. 2 is a front/left-side/top perspective view thereof in a hanging position.

1 Claim, 2 Drawing Sheets

FIG. 1

FIG. 2

UNITED STATES PATENT AND TRADEMARK OFFICE
CERTIFICATE OF CORRECTION

PATENT NO. : Des. 490,650 S
DATED : June 1, 2004
INVENTOR(S) : Lambertus J. M. Van Geenen

Page 1 of 1

It is certified that error appears in the above-identified patent and that said Letters Patent is hereby corrected as shown below:

Title page.

Item [30], Foreign Application Priority Data, "BJ" should read -- BX --.

Signed and Sealed this

Ninth Day of November, 2004

JON W. DUDAS
Director of the United States Patent and Trademark Office
